(57) **CLAIM**

The ornamental design for a cutting machine having a reduced form factor, as shown and described.

DESCRIPTION

FIG. 1 is a front, left, top isometric view of a first embodiment of a cutting machine having a reduced form factor; FIG. 2 is a rear, left, bottom isometric view thereof; FIG. 3 is a front elevation view thereof; FIG. 4 is a rear elevation view thereof; FIG. 5 is a left elevation view thereof; FIG. 6 is a right elevation view thereof; FIG. 7 is a top plan view thereof; FIG. 8 is bottom plan view thereof; FIG. 9 is a front, left, top isometric view of a second embodiment of a cutting machine having a reduced form factor; FIG. 10 is a rear, left, bottom isometric view thereof; FIG. 11 is a front elevation view thereof; FIG. 12 is a rear elevation view thereof; FIG. 13 is a left elevation view thereof; FIG. 14 is a right elevation view thereof; FIG. 15 is a top plan view thereof; and, FIG. 16 is bottom plan view thereof.

The dotted and dashed broken lines immediately adjacent to the shaded areas depict the bounds of the claimed design, while all other broken lines are directed to environment. The broken lines form no part of the claimed design.

The “Cricut” lettering and/or icon forming part of the disclosure is a registered trademark of Cricut, Inc.
